United States Patent [19]

Barron et al.

[11] Patent Number: Des. 310,356

[45] Date of Patent: ** Sep. 4, 1990

[54] VIDEO MONITOR

[75] Inventors: Peter B. Barron, Leominster, Mass.; Allan Weaver; Margaret A. Maas, both of Hollis, N.H.

[73] Assignee: Digital Equipment Corporation, Maynard, Mass.

[**] Term: 14 Years

[21] Appl. No.: 160,492

[22] Filed: Feb. 25, 1988

[52] U.S. Cl. D14/113

[58] Field of Search D14/100, 101, 102, 103, D14/105-107, 126, 113-115; D18/1, 7, 11, 12; 340/700, 706, 711, 712; 341/22, 23; 358/249, 254; 364/706-710

CLAIM

The ornamental design for a video monitor, as shown and described.

DESCRIPTION

FIG. 1 is a front, right side perspective view of a video monitor showing our new design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof.

Fig. 1.

Fig. 2.

Fig. 3.

Fig. 4.

Fig. 5.

Fig. 6.

Fig. 7.
